ABSTRACT OF THE DISCLOSURE

A multi-step solvent extraction process is described for the preparation of lube oil products wherein the selectivity of the solvent is maintained in at least one of the extraction steps suitable to yield a raffinate lube oil product which has the equivalent of a light neutral V.I. level of at least about 120 V.I. after dewaxing and effecting the extraction in a process environment which will substantially reduce the solvent dosage required to produce the high V.I. oil product in combination with a lower V.I. oil product and often raise the yield of the desired oil products.

Background of the invention

Solvent extraction is a well established process used in the refining of petroleum, the first application having been made in about 1911. Originally, upgrading of kerosine was a major use but the improvement obtained in solvent extracting lubricating oils and others soon became an important application. Solvent extraction is used extensively in the petroleum refining industry to refine lubricating oils, kerosine and specialty oils for medicinal and agricultural purposes. Solvent extraction has also been used for the upgrading of charge stocks for catalytic cracking operations as well as the separation of light aromatics from gasoline. Solvent extraction is a process that separates hydrocarbon mixtures into two phases; a raffinate phase which contains substances of relatively high hydrogen to carbon ratio often called paraffinic type materials and an extract phase which contains substances of relatively low hydrogen to carbon ratio often called aromatic type materials. Therefore, it may be said that solvent extraction is possible because different liquid compounds have different solution affinities for each other and some combinations are completely miscible while other combinations are almost immiscible. The ability to distinguish between high carbon to hydrogen aromatic type and low carbon to hydrogen or paraffinic type materials is termed selectivity. The more finely this distinguishing can be done the higher the selectivity of the solvent.

For example, it is known that lube oils are exceedingly complex hydrocarbon mixtures made up principally of paraffins, naphthenes, aromatics and asphalts and the chemical constitution of oils stable to oxidation can only be guessed. That is, it is known that the polynaphthenic type materials oxidize more readily to degradation products such as acids and/or insoluble asphaltenes than do those of paraffinic type. The latter usually tolerate oxidation at moderate temperatures for extended periods before visible signs of change appear, but it is not clear or certain that soluble oxidation products are not accumulating during this period. In agreement with this is the fact that the oxidation of mixed naphthenic oils is retarded by solvent extraction which removes the polynaphthenes and polyaromatics.

It is known from work of others that oil is made up of compounds consisting of naphthenic and aromatic rings carrying side chains of varying number, length and structure. Long side chains are characteristic of molecules of high paraffinicity and high viscosity index, while poly-

2

naphthenic and polyaromatic structures with fewer and shorter chains will show low viscosity index, high viscosity-gravity constant and relatively poor stability against oxidation. The division between compounds of long and short side chains, therefore, is necessarily not sharp and undoubtedly some constituents of good quality are lost in any extraction process.

Terms which are used extensively in solvent extraction operations include "solvent" for the extracting agent, "solute" for the readily soluble material in the feed, "extract" for the material removed from the feed, "raffinate" for the non-dissolved product, and "reflux" for extract material returned to the extractor. "Lean solvent" refers to the solvent as charged to the extractor; "rich solvent" refers to the solvent extract solution withdrawn from the extractor.

Solvents which have been used in commercial operations include furfural, phenol, cresylic acid, nitrobenzene, dichloroethyl ether, sulfur dioxide and others. If desired, these solvents may be used in the presence of diluents such as benzene, carbon disulfide, ethers and carbon tetrachloride. Generally the diluents increase the solubility of all of the hydrocarbons. The use of diluents however can reduce solvent selectivity.

Furfural is typical of a suitable solvent extraction agent. Its miscibility characteristics and physical properties permit use with both highly aromatic and highly paraffinic oils of wide boiling range. Diesel fuels and light and heavy lubricating stocks are refined with furfural. For lubricating oils it has been used in the prior art at elevated temperatures in the range of 120° F. to 290° F. and with from 1 to 4 volumes of furfural to 1 volume of oil. Furfural exhibits good selectivity at elevated temperatures (175–250° F.); this characteristic results in the benefits of reduced viscosity and high temperature gradient and permits operation on waxy stocks. In a typical furfural solvent extraction plant for lubricating oils, the raw feed or distillate fraction, at a temperature of about 110 to about 250° F. and depending upon the nature of the oil, is introduced below or about the center of the extraction tower. Furfural is fed into the top or upper portion of the tower at a temperature selected from within the range of about 150° F. to about 290° F. Recycle extract may be introduced into the lower section of the tower as reflux. Likewise, internal reflux is effected in the tower by the temperature gradient which is brought about by introducing the solvent at an elevated temperature and by intermediate cooling systems. Furfural solvent is recovered from the raffinate and extract phase streams or layers in suitable distillation and stripping equipment. The stripped and recovered solvent is then returned or recycled for use in the process as above described.

Finished lubricating base oils are generally divided into the following three broad grade classifications:

	Viscosity Range, Saybolt Seconds Universal	Boiling Range, ° F.
Light neutrals.....	100–250 at 100° F.....	650–900° F.
Heavy neutrals.....	350–700 at 100° F.....	850–1,000° F.
Bright stocks.....	110–200 at 210° F.....	>950° F.

The light and heavy neutrals are normally produced from adjacent boiling vacuum tower distillates that are solvent extracted and dewaxed. The bright stock is produced from the vacuum tower residuum remaining after the light and heavy neutral distillates have been boiled off. The residuum is first deasphalting and the deasphalted oil is then solvent extracted and dewaxed. It has been found that these three grades of unrefined stocks from any given lube crude have markedly different refining requirements to achieve normal quality levels as measured by viscosity index. The heavier higher boiling stocks from a crude are

more difficult to refine to a given viscosity index level than is the adjacent lower boiling fraction. Therefore under the conditions described in this invention, "high" viscosity index products from a given crude will vary with viscosity grade as follows:

	High viscosity index product, plus
Light neutral	120
Heavy neutral	115
Bright stock	110

These numerical V.I. levels thus represent equivalent extraction severities for the several viscosity grades of products. The V.I. rating of lubricating oil products can then be generally described in terms of any one of these viscosity grades in accordance with this relationship.

Lube crude oils are classified by the Bureau of Mines into three categories according to the predominant composition of their 736-788° F. fraction as paraffinic, intermediate and naphthenic. Paraffinic crude such as Pennsylvania or High Pour Libyan crudes contain considerable amounts of wax, while some naphthenic crudes such as coastal crudes contain no wax. Intermediate crudes such as Mid-Continent, Kuwait or East Texas contain varying amounts of both wax. Thus it can be seen that crude source is especially important in the manufacture of premium lubricants as various lubrication duties require oils of different chemical composition and properties.

Results of a relatively broad literature review indicate that relatively high V.I. lube oil components and above about 120 V.I. are present in many crude lube oil fractions. However, recovery of these high V.I. components in a stable oil fraction has been the subject of considerable investigation. It has been found upon review of the prior art and literature methods for recovering high V.I. lube oil constituents that the processes employed are generally regarded as exotic extraction and distillation schemes which are of little or no commercial interest primarily because of cost involved.

It has been demonstrated that a 125 V.I. oil can be produced from a dewaxed Pennsylvania light neutral stock by exhaustive leaching with acetone. The procedure and solvent employed are considered to be unacceptable for commercial application. It has also been found that relatively high yields of non-aromatic oils which have the equivalent of a light neutral V.I. level of 109-121 can be separated from finished paraffinic lubes by silica gel adsorption. The separation scheme covered employs extremely high silica to gel ratios and has proved to have little commercial potential.

Basically all extraction processes are similar. Each consists of facilities to contact the oil with a selective solvent that separates by extraction one or more types of the oil constituents from other types of oil constituents plus facilities to separate solvent from the extract and raffinate streams thus obtained. The solvent must be recovered in substantially every circuit of the system. As large amounts of solvent are circulated, the heat requirements are high and unless employed in extremely efficient manner, they constitute one of the major operating expenses. The extraction equipment proper is relatively simple but the solvent recovery facilities are necessarily complex and therefore expensive and any means by which these costs or facilities can be simplified greatly contribute to the commercial interests of the process.

Summary of the invention

Generally speaking, the present invention is concerned with a method of recovering a high V.I. lube oil product from a lube oil crude to the exclusion of undesired constituents by a solvent extraction process in an environment which emphasizes the solvent selectivity and improves the yields of a lower V.I. lube oil product recovered simultaneously therewith. Thus the present invention is particularly concerned with the method and combination of processing steps for producing lubricating oil prod-

ucts having at least two different V.I. levels; one of which has the equivalent of a light neutral V.I. level upon dewaxing of at least about 120 V.I. or the equivalent of a heavy neutral V.I. level upon dewaxing of at least 115 and the other has a lower V.I. level; but above 90 V.I. after dewaxing. (Of course the higher the viscosity, the lower will be the V.I. level.)

In accordance with one embodiment within the concept of the present invention, a lube oil crude fraction of hydrocarbon feed stock boiling above about 550° F. is contacted countercurrently with solvent, such as furfural, in a first extraction column comprising a plurality of separate and sequentially arranged extracting steps under conditions of temperature and solvent concentration to improve the solvent selectivity and permit recovering therefrom a primary lube oil raffinate fraction which will produce upon dewaxing a lube oil product of at least 90 V.I. and preferably at least about 95 V.I. The primary raffinate fraction thus separated from the first extractor and prior to dewaxing is passed in part or all thereof to a second extractor comprising a plurality of sequentially arranged separate extraction stages. In the second extractor the selectivity conditions of the furfural solvent are maintained beyond that hereinbefore thought economic by employing solvent to oil ratios of at least 7:1 and preferably as high as possible and of the order of about 10:1 so as to recover from the primary raffinate phase a secondary raffinate lube oil product phase which is stable to oxidation and light while providing upon dewaxing a lube oil product having the equivalent of a light neutral V.I. level of at least 115 and preferably as high as about 125 V.I. By the above combination in which a relatively high V.I. primary raffinate of at least 90 V.I. is further subjected to a very selective solvent extraction operation under such conditions of high solvent to oil ratio, it has been found that the overall solvent dosage requirements of the process can be held to a desired minimum and substantially reduced volumewise over that required to produce the highest V.I. oil desired in, for example, a single extractor column. Thus it can be seen that the extraction sequence above described and concerned with the essence of the present invention departs significantly from the known prior art by employing solvent dosages in at least one step which is far above that employed hereinbefore and is generally in excess of about 8:1 with respect to the oil phase being treated so as to maximize the selectivity of the furfural solvent. A second phase of the present invention is concerned with the treatment given the second extract phase of the process so that the process is integrated in an economically attractive manner for commercial application. In this regard the secondary extract fraction is cooled, add an anti-solvent such as water or both to a temperature which is suitable for releasing from the solvent an oil rich phase of desired V.I. upon dewaxing. The oil phase may be separated by decanting so as to recover from this secondary extract the desired first oil rich phase or fraction which is suitable for use or blending with at least a portion of the first raffinate phase from a concentrated solvent fraction or solvent rich phase. It has been found that this decanted first oil rich phase is of a composition which is suitable for use as is or it may be used for blending with the primary raffinate product obtained from the first extractor and used to produce the lube oil of lower V.I. above about 90, thus contributing to an overall yield improvement in the oil products attained from the hydrocarbon charge. The decanted solvent rich phase obtained from the second extract is recovered and all or a portion thereof is passed directly, after adjusting its temperature, for use in the first extractor of the process either alone or in combination with some fresh makeup furfural. It is contemplated, however taking a portion of this decanted solvent rich phase and purifying it by passing it to a solvent recovery system wherein an aromatic rich oil phase is recovered from the solvent phase and a purified solvent is recovered which may be recycled all or in part to either

the first or second extractor as desired. On the other hand, if all of the decanted solvent rich phase is passed to the first extractor, the first extract phase will then be treated in a suitable solvent recovery system to recover a purified solvent rich phase from an aromatic rich oil phase. In the arrangement of the process above described, it is to be particularly noted that a significant portion of the process above described is particularly concerned with and directed to improving the overall economics of the process by minimizing the volume of solvent required, the solvent recovery stages required and taking advantage of the improved selectivity of the solvent rich second extract phase to obtain not only the solvent requirement of the first extractor but also to recover from the second extract those oil constituents which are suitable for blending with an oil product recovered from the first raffinate phase.

Thus it can be seen that significant economic advantages and solvent selectivity are realized by the method and combination of process steps of the present invention. In conjunction with maximizing the selectivity of the furfural solvent, the present invention permits the recovery of the unusually high V.I. contributing constituents of oil crude sources in a manner not heretofore realized as economically attractive.

Thus the particular method of operation and combination of processing steps is selected so as to realize solvent selectivity and economic advantages only possible by the particular process combination herein described and highly suitable for commercial application.

Brief description of the drawing

The drawing presented herewith diagrammatically presents an arrangement of processing steps for practicing the method of the present invention to produce a high V.I. lube oil product, an intermediate V.I. lube oil product and an aromatic rich oil product as described herein.

Description of specific embodiments

Referring now to the drawing, by way of example, there is provided an arrangement of processing steps for producing lube oil fractions from a hydrocarbon charge material such as a lube oil containing distillate fraction obtained from a Kuwait charge oil. In the arrangement of the drawing, a 120 SSU at 130° F. distillate fraction of a Kuwait crude is introduced by conduit 2 to a first extractor 4. Extractor 4 is provided with at least 5 stages of contact with furfural introduced to an upper portion of extractor 4 by conduit 6. In the operation of extractor 4, furfural is introduced to the upper portion of the extractor for countercurrent flow therein with the distillate charge introduced to the lower portion of the extractor, under conditions to maintain a temperature therein selected from within the range of from about 125° F. to about 210° F. and preferably of the order of about 190° F. An extract phase is withdrawn from the bottom of the extractor 4 by conduit 8. A raffinate phase, and comprising a paraffin rich lube oil product of desired intermediate V.I. upon dewaxing is withdrawn from the top of extractor 4 by conduit 10. A portion of the first or primary raffinate phase in conduit 10 is passed by conduit 12 to a dewaxing section 14. The remaining portion of the primary raffinate in conduit 10 is passed to a second extractor 16 and comprising 7 extraction stages. In extractor 16 the solvent extraction conditions are maintained sufficiently intense or severe by using a large excess of furfural to remove from the primary raffinate product a sufficient amount of the low V.I. producing constituents of the primary raffinate comprising paraffins in conjunction with high boiling polycyclic aromatic compounds not desired in the high V.I. lube oil product being produced. In extractor 16 it is contemplated employing a large excess and from about 800 to about 1500% furfural to effect the intensity of extraction desired at a temperature maintained as low as possible and within the range of 175 to about 250° F. A temperature above about 225° F. is regarded as an excessive temperature for treat-

ment of light neutrals. In the specific arrangement of the drawing, sufficient furfural solvent is introduced into the upper portion of extractor 16 by conduit 18 for countercurrent flow therein to the primary raffinate introduced to the extractor by conduit 10. The raffinate phase of extractor 16 and comprising the secondary raffinate is removed from the upper portion of extractor 16 by conduit 20. This secondary raffinate is passed after stripping of solvent therefrom to a dewaxing zone 22 maintained at a sufficiently low dewaxing temperature such as about -20° F. in a specific embodiment. Wax is recovered from the dewaxing zone 22 by conduit 24 and a dewaxed oil of about 123 V.I. is recovered by conduit 26. The secondary extract phase obtained by extractor 16 is removed from the bottom thereof by conduit 28 for passage to a cooling zone 30 and conduit 32 to a separation zone 34. Separation zone 34 is maintained at a temperature of about 100° F. so as to recover a paraffin rich oil phase separated from an aromatic rich extract phase. The paraffin rich oil or raffinate phase thus separated is removed from separator 34 by conduit 36 and is passed to dewaxing zone 14 either alone or in combination with the portion of the primary raffinate in conduit 12 being passed to the dewaxing zone. In a specific embodiment, dewaxing zone 14 is maintained at a temperature of about 0° F. so as to recover wax from the oil product. In this specific embodiment, an oil product of about 95 V.I. is recovered from dewaxing zone 14 by conduit 38 and the wax product is removed therefrom by conduit 40. The aromatic rich extract phase developed in separation zone 34 is removed from the lower portion thereof by conduit 42. The aromatic rich extract in conduit 42 may be combined with the extract phase in conduit 8 or may be separately processed to recover solvent from aromatic product. In the specific arrangement shown, the mixed extract phase is passed by conduit 44 to a furfural or solvent stripper 46. Solvent is recovered from the upper portion of stripper 46 by conduit 48 and an aromatic rich oil phase is recovered from the bottom of stripper 46 by conduit 50. In the arrangement of the drawing, above described, it is to be understood that all or a part of the primary raffinate phase in conduit 10 may be passed to the second extractor 16 and the amount passed thereto may be contingent, at least in part, upon the volumes of high and intermediate lube oil products desired by the individual refiner. It is also to be understood that a furfural stripper is necessary in conduits 20 and 12 prior to passing the oil product to the dewaxing step and such furfural strippers being known in the prior art are part of this invention only to the extent required to recover solvent from the desired oil product. The specific processing scheme, above described, departs from the known prior art in the concept of operating the secondary extractor under such intense conditions of extraction severity so as to permit recovery of a secondary raffinate phase which upon dewaxing will provide a desired 0° F. pour, high V.I. lube oil product of at least about 120 V.I. This method of operating the second extractor under such intense conditions of severity and high concentrations of furfural in combination with the recovery of oil products from the secondary extract of a composition suitable for combining with the oil in the primary raffinate portion and used to prepare the intermediate lube oil of about 95 V.I. and 20° F. pour is a significant departure from the known prior art.

Example I

Raw and dewaxed High Pour Libyan (HPL) 114 SSU at 130° F. distillates were furfural extracted at high furfural dosages and extraction efficiencies to determine the extent of producing high viscosity index oils through crude selection and use of regular solvent extraction equipment. In this example seven stages of extraction were effected at 200° F. temperature and 1,000% furfural dosage. Extraction under these conditions produced an oil upon

dewaxing of 125 V.I. Effecting a similar solvent treatment at 500% dosage produced a 113 V.I. oil product. The yield obtained varied from 2.6-2.9% volume on crude for the 125 V.I. oil to 4.1-4.6% for the 113 V.I. oil.

Example II

Table 1 below presents the results of solvent furfural extraction at high furfural dosages of at least 10:1 when effected in the manner described with respect to Example I for other charge stocks identified in the table. It is to be noted that the high solvent dosages produced V.I. oils of at least 120 irrespective of the crude employed.

* Sample in clear 4 oz. bottle on window sill for 3 months.

Example III

Table 2 below presents the results obtained when preparing a 123 V.I. light neutral by deep solvent extracting 114 SSU at 130° F. Kuwait distillate in the two

extractor process hereinbefore described. It will be noted from Table 2 that the raffinate from extractor No. 1 is used as charge to the extractor No. 2. It is also to be noted that by effecting the solvent extraction in the two extractor system as hereinbefore described that considerable economic savings can be realized in the amount of solvent required since the barrels of raffinate charged to the second extractor wherein the high solvent dosage is employed is considerably less than when carrying out the same solvent dosage in a single extractor system such as presented by Table 1.

Example IV

Table 3 below presents the results obtained when preparing a 118 V.I. heavy neutral from a 453 SSU at 130° F. Kuwait distillate by deep solvent extraction with furfural. The data of the table is arranged similarly to that presented in Table 2 for purposes of comparison. Thus in this example it is shown that the two extractor system is capable of producing two different V.I. lube oil products of 94 and 118 V.I. and the dewaxed oil separated from the second extract has a V.I. of 93 and this is suitable for blending with the 94 V.I. product obtained from the first extractor and it may be used in place thereof. Thus the method and combination of processing steps of this invention permit the preparation of two different V.I. lube oil products by passing all or a portion of the first raffinate to the second extractor so that a high V.I. lube oil product can be recovered from the second raffinate and a lower V.I. lube oil product can be separated from either or both of the first raffinate and the second extract.

Having thus provided a general description of the method and process of the present invention and provided specific examples in respect thereof, it is to be noted that no undue restrictions are to be imposed by reason thereof except as defined by the appended claims.

We claim:

1. A method for producing lubricating oils by solvent extraction which comprises:

(a) contacting a lube oil containing hydrocarbon charge material with solvent in a first extraction zone containing a plurality of separate extraction stages under conditions of solvent selectivity to permit recovering a first lube oil raffinate phase which upon dewaxing will provide a lube oil product of at least about 90 V.I.,

(b) further contacting a portion of the first lube oil raffinate phase in a second extraction zone containing a plurality of separate extraction stages under conditions of solvent selectivity attainable only by employing solvent to oil ratios of at least about 7 to 1.

(c) recovering a second lube oil raffinate phase from said second extraction zone which upon dewaxing will provide a lube oil product having the equivalent of a light or heavy neutral oil V.I. rating of at least about 115,

(d) recovering an extract from said second extractor,

(e) cooling and decanting said extract under conditions of temperature which permit the recovery of an oil phase having upon dewaxing a V.I. of at least about 90 and suitable for blending with a dewaxed lube oil product obtained from the first raffinate phase and

(f) passing a portion of a solvent rich phase remaining from decanting said extract to said first extractor as a substantial portion of the solvent requirements thereof.

2. The method of claim 1 wherein from about 130 to about 200 volume percent of solvent is employed in the first extractor and from about 700 to about 1500 volume percent of solvent is employed in the second extractor.

3. The method of claim 1 wherein the solvent is furfural and the temperature of the extractors is maintained in the range of from about 175 to about 250° F. and the temperature is maintained below about 225° F. when processing light neutrals.

4. The method of claim 1 wherein the solvent to oil ratio is at least 10 to 1.

5. The method of claim 1 wherein the dewaxed second raffinate provides a lube oil product having the equivalent of a light neutral oil V.I. rating of about 125.

6. The method of claim 1 wherein the dewaxed second raffinate provides a lube oil product having the equivalent of a heavy neutral oil V.I. rating of at least about 115.

7. The method of claim 1 wherein the solvent is selected from the group consisting of phenol, SO_2 and furfural.

8. The method of claim 1 wherein all of the first raffinate is passed to the second extractor.

9. The method of claim 1 wherein a portion of the first raffinate is dewaxed to produce a lube oil product of at least about 90 V.I. and the remaining portion of the first raffinate is passed to the second extractor.

10. The method of claim 1 wherein a second extract is recovered from the first extractor and stripped to recover solvent from an aromatic rich oil phase and said stripping is effected with or without a portion of the solvent rich phase recovered from said decanting step combined therewith.

11. The method of claim 1 wherein all of the lube oil product containing streams are stripped of solvent before effecting dewaxing thereof.
